HOOD CONSTRUCTION

William J. Hall, Detroit, Mich., assignor, by
mesne assignments, of thirty per cent to Ollie
L. Herron, thirty per cent to Joseph B. Zimmers,
thirty-three per cent to William J. Hall, and
seven per cent to R. C. Schemmel

Application January 25, 1932, Serial No. 588,566

5 Claims. (CL 16—178)

This invention relates to hinge constructions and it has particular relation to a hood and manner of hinging the wings of the hood.

One object of the invention is to provide an improved hood construction having wings hinged on an intermediate support in such manner that the hinges are concealed, thereby greatly enhancing the appearance of the hood, it being apparent that if the wings smoothly operate in a pivotal manner, without visibly revealing the hinging relation of the support and wings, the smooth and stream line appearance of the vehicle will be greatly improved.

Another object of the invention is to provide a hood having wings so hinged that the exposed surfaces of the hood adjacent the hinging parts as well as the exposed surfaces of the support in this location will not be marred or scratched during hinging movement of the wings. It follows that the finish of the hood and support will not be impaired, or at least those surfaces which are visible will not be marred or scratched and the appearance of the finish will remain the same as the body of the hood.

Another object of the invention is to provide a hood having wings hinged in such manner that the exposed and finished surfaces of the hood will not come into contact during movement of the wings.

Another object of the invention is to provide a hood having hinged wings in which the hinging parts are so constructed and related that either wing may be maintained in a raised or lowered position when moved to either of said positions.

Another object of the invention is to provide a hood having hinged wings which can be manufactured from rolled sheet metal thereby dispensing with the use of the usual auxiliary hinged parts ordinarily manufactured separately of the hood and subsequently associated therewith.

Other objects of the invention will be apparent from the description and drawing relating thereto, and the claims which have been set forth.

For a better understanding of the invention reference may be had to the accompanying drawing forming a part of the specification, wherein:

Figure 1 is a fragmentary plan view of an automobile having a hood constructed according to one form of the invention;

Fig. 2 is a cross-sectional view on a larger

scale taken substantially along line 2—2 of Fig. 1 but showing the hood in perspective; Fig. 3 is a view similar to that shown by Fig. 2 illustrating the manner in which the hood wings may be moved into their raised and opened positions;

Fig. 4 is a larger view in cross section more particularly illustrating a preferred construction and relation of the hinged parts on the wing and support therefor.

Referring to Figs. 1 and 2, an elongated plate element 10 is provided which is constructed preferably of sheet metal, and this element at opposite ends ordinarily will be secured to a radiator 11 and cowl 12 of an automobile. The plate 10 constitutes a hinge support for hood wings 13 and 14, preferably identical in construction although oppositely disposed, and consequently, a description of the manner of constructing the wing 13 and the manner in which it is hinged to the element 10 seems sufficient.

The wing comprises preferably a plane portion 15 terminating in an inwardly extending flange 16 which abuts a flange 17 of a hinge part 18, such flanges being connected by rivets or any other suitable means such as spot welding the flanges at spaced points. The hinge part 18 at the upper edge of the flange 17 is rolled to form a male hinge element and the element or plate 10 at its adjacent edge is rolled to form a female element. Such male and female elements then may be associated by telescoping the parts longitudinally.

As an example of a preferred arrangement of surfaces, and relation of different parts of the male and female members, attention is directed to Fig. 4 which illustrates the parts on a large scale. In this construction the upper end of flange 17 joins a curved portion 20 having a center of curvature indicated at 21, the radius of the outermost surface being approximately $7/64$ of an inch. This curved portion preferably terminates approximately at the line 22, and joins an approximately straight portion 23 which extends substantially to the line 24. From the line 24 to approximately the line 25 the hinge part is curved as indicated at 26, about a center 27, the radius of curvature of the outermost surface being approximately .242 inches. From the line 25 to the line 28 the hinge part is curved as indicated at 29 about a center 30, the radius of curvature of the outermost surface being approximately .164 inches. From the line 28 to approximately the line 31 the hinge part is curved as indicated at 32 about a center 33,

the radius of curvature of the outermost surface being approximately .125 inches. From the line 31 to the end edge 35 of the hinge part, the latter is curved as indicated at 34 about a center 5 36, the radius of curvature of the outermost surface being approximately .062 inches. The outermost surface of the curved portion 34 nearest the substantially plane portion 23 of the hinge part 18 normally will be disposed very closely 10 adjacent to the plane of the body 15 of the wing 13, or slightly below such body portion, as shown by Fig. 4, and for this reason it would be rather difficult from a practical point of view to roll the male hinge part unless the body 15 of the 15 wing were manufactured separately of the hinge part and subsequently connected thereto by means of the flanges 16 and 17 in the manner previously described.

On the element 10, from approximately the 20 line 40 to the line 41, a curved portion 42 is provided having a center of curvature substantially coinciding with the point 33 previously mentioned, the radius of curvature of the innermost surface being approximately .129 inches or, 25 in other words, slightly greater than the radius of curvature of the outermost surface of portion 32 of the hinge part 18. From the line 41 to the inner end of the hinge part of element 10, indicated at 44, a curved portion 45 is provided having 30 a center of curvature substantially coinciding with the center 36, and a radius of curvature of its innermost surface, of approximately $\frac{1}{8}$ of an inch.

From the above description it will be apparent 35 that the element 10 has a rolled portion comprising parts 42 and 45 which are of circular character, but that such circular portions have different centers of curvature, namely, the centers 33 and 36, as well as different radii. It 40 also will be noted that the inner end of the rolled portion of the element 10 indicated at 44, terminates at a point sufficiently spaced from the inner surface of circular portion 42, to permit proper manipulation of the hinge part 18 45 with respect thereto. It also will be apparent that the hinge part 18 from the straight portion 23, gradually extends in a generally spiral manner to the terminal edge 35, and that the spiral formation comprises true curved portions 26, 29, 50 32 and 34 having different radii and centers. It also will be noted that the radius of curvature of the outermost surface of portion 34 substantially corresponds to the radius of curvature of the innermost surface of portion 45 of the element 55 10, and that the radius of curvature of the innermost surface of portion 42 on element 10, substantially corresponds to the radius of curvature of the outermost surface of portion 32 on the hinge part 18. Hence, when the hinge is in 60 its closed position as shown by Fig. 4 as well as Fig. 2, the outer surface of portions 32 and 34 of the male member or hinge part 18, substantially contact with the inner surfaces of portions 45 and 42 of the female hinge element 65 10.

When the wing is moved toward open position as shown by Fig. 3, it appears that pivotal movement occurs about a point approximately located at 50 and that as the wing approaches 70 open position, the inner surface of the portion 34 of the male hinge element hooks over the extremity 44 of the female hinge part as shown in Fig. 3. This hooking feature serves to limit the wing in its opening movement as well as to 75 positively retain it in open position because

when so opened, the wing is in an over-balanced position as clearly shown by Fig. 3. When the wing is in its closed position it is apparent that the engagement of complementary surfaces on the hinging parts positively limits its closing movement and hence serves in a sense to hold the wing in proper position.

While it has been stated that pivotal movement of the wing seems to occur approximately about a point indicated at 50 in Fig. 4, this point 10 seems to change somewhat during final opening movement of the wing, and as the wing approaches its open position the point seems to move downwardly slightly along the inner surface of the curved portion 45 of the female member 15 away from the end 44 thereof.

Referring to Fig. 2, it is apparent that vision of the exposed surfaces of the hinge parts, for instance, substantially may be limited to the point 60 on the female member and substantially 20 the point 61 on the male member, or in other words, if an observer were to look through the space between the female hinge part on the element 10, and the body portion of the wing, the surfaces would be visible substantially only to 25 the points 60 and 61. Now during hinging movement of the wing, such visible surfaces normally will not contact with any other surface and, consequently, will not be marred or scratched, and after the wing is again closed, the visible surfaces will still have their initial finish. This is 30 highly advantageous because the preservation of exposed surfaces of a motor vehicle, is quite important from the vehicle appearance point of view.

In general, the male and female parts of the hinge are so designed that when assembled together by sliding the male section into the female section, a smooth working, shake proof hinge results, which can at no time during the 40 whole working range of pivotal movement come into contact with the visible parts of the hinge, thereby preserving the finish and preventing an unsightly appearance. Moreover, the hinge parts are so constructed and related, that they 45 cannot come apart except in precisely the same manner as that in which they are assembled, or in other words they must be assembled and disassembled in a telescopic manner. Furthermore, the hinge prevents water and the like from 50 entering the motor space under the hood.

Attention is directed to the fact that the curved hinge portions of the male members on both hood wings are spaced as shown in Fig. 2, and that this space increases as the wings are 55 opened as shown in Fig. 3. It would be possible to have such parts of the male members contact with the wings in closed position, since they move apart in opening, but no contact is necessary, and they may be spaced at all times as 60 illustrated.

It is apparent that a novel form of hinge construction as well as hood construction, has been provided, which enables operation of the hood 65 wings easily, and in a nice, smooth working manner. Moreover, it is apparent that the hinge can be constructed efficiently and inexpensively by rolling the metal into the form described, and that the hinge parts may readily be assembled by telescoping the male part into the female 70 part. It is also apparent that a hinge has been provided for a hood, which insures preservation of the exposed and finished surfaces of the hood, and eliminates scratching or otherwise marring 75 of any surfaces during hinging movement of the 75

wings, which would be visible particularly when the wing is in its closed position, in which position it is in practically all of the time. Moreover, it is apparent that the hinge provides means for limiting and holding the wing in its open position, which is quite advantageous when it is desired to obtain access to the vehicle motor by raising one of the hood wings. The several advantages manifestly are quite important in the vehicle manufacturing industry, not only from a manufacturing point of view, but from the operating point of view after the hood is purchased from the manufacturer.

Although only one form of the invention has been illustrated and described in detail, it will be apparent to those skilled in the art that various modifications may be made without departing from the scope of the appended claims.

I claim:

20. 1. A hinge comprising plate elements having interengaging rolled edges, one plate having a curved sector adjacent its edge, and a second curved sector at its edge which has a smaller radius of curvature, the other plate having a curved edge sector adapted to receive the smaller curved sector of the first plate when the plates are in one position, the first mentioned sector when the plates are related as last mentioned, being spaced from and free to move through a substantial hinging movement without engaging the outer surface of the second plate curved sector, but being substantially complementary thereto and engaging it after such hinging movement, the second curved sector on the first plate being adapted to receive and hook over the free edge of the second plate during such hinging movement.

25. 2. A hinge comprising plates having interengaging rolled edges, one edge terminating in a curved sector substantially complementary to and fitting in a curved sector of the other edge when the plates are in one position, such inner edge sector being curved about a small radius and the length of the arc being such as to provide a hook, the entry of which substantially corresponds to the thickness of the other plate edge, whereby during hinging movement to move the inner curved sector out of surface engagement with the outer sector, the edge of the latter enters the hook portion.

30. 3. A hinge comprising plates having inter-

engaging curved edges, one within the other, the inner curved edge having a substantial arc portion, the outer surface of which fits against the inner surface of a substantial arc portion of the other rolled edge when the plates are in one position, the first mentioned arc portion terminating in a curved hook, the entry to which is substantially the same in dimensions as the thickness of the edge of the other plate, so that during hinging movement, the edge may move into the hook.

35. 4. A hinge for hoods comprising a plate having one edge portion curved downwardly and then toward the center of the plate, with the free edge terminating in spaced relation to the plate body to provide an entry opening, and a second plate extending along the edge of the first plate and having a hook-shaped edge portion nested in the curved portion of the first plate when the parts are in one position, and also having a portion extending through such entry opening and then partially about, and in substantially spaced relation to the outer surface of the first curved edge portion, the hook-shaped edge portion on the second plate receiving the free edge of the curved portion of the first plate after a predetermined hinging movement, to lock the parts together.

40. 5. A hood hinge comprising, a pair of plate members disposed in side-by-side relation, one plate member having its edge portion adjacent the other, curved downwardly and then reversely toward the center of the plate to provide a hook-shaped portion having its entry opening toward the center of the plate, the other plate having its edge portion adjacent the first plate, provided with a curved portion nesting in the hook-portion of the first plate when the plates are in one position, and having a portion extending through the entry opening of the first curved portion and then in substantially spaced relation to the outer surface of the latter curved portion, the curved portion on the second plate receiving the free edge of the curved portion on the first plate when the second plate is hinged relative to the other, the parts being so related as to prevent the substantially spaced portion on the second plate from engaging and marring surfaces on the first plate and its curved portion, visible from the upper sides of the plates.

45. 50. WILLIAM J. HALL.
